CONNECTING MEANS FOR COUCH FRAMES OR THE LIKE

Filed June 5, 1929

UNITED STATES PATENT OFFICE

HARRY MINTZ, OF DORCHESTER, MASSACHUSETTS

CONNECTING MEANS FOR COUCH FRAMES OR THE LIKE

Application filed June 5, 1929. Serial No. 368,535.

This invention relates to beds, couches, couch hammocks, and the like, and the principal object of the invention is to provide improved means for removably connecting the side rails, tie bars, or braces to the respective head and foot members, standards, arm rests, or the like, to hold the latter in vertical, parallel relation.

A recommended embodiment of the invention as applied specifically to a couch hammock is illustrated in the accompanying drawings, in which:

Fig. 1 is a fragmentary front elevation of a couch hammock equipped with the improved connecting means; with a portion of its structure shown in section;

Fig. 2 is an enlarged broken section taken in the line 2—2 of Fig. 1;

Fig. 3 is a detail view of the sectional portion of Fig. 1 to larger scale; and

Fig. 4 is an end view of the longitudinal bracing member.

The couch hammock as shown comprises a pair of spaced end standards including a base member 5; a pair of uprights 6 and an upper cross bar 7; a swinging couch, including upholstered seat and back members 8 and 9 respectively, suspended between the standards by means of straps 10 connecting the ends of the cross bar 7 with braced legs 11 carried by the seat 8; and a longitudinal tie bar or rail 12 detachably connected at its opposite ends to the respective standards rigidly to support the latter in upright position. As the present invention pertains more particularly to the separable connection between the rail ends and the standards, the precise construction and arrangement of the other elements of the structure need not be further described.

As shown, the base 5, uprights 6, and brace-bar 12 are preferably formed of angle iron of suitable strength and rigidity, and the uprights are affixed to the vertical web of the base in spaced parallel relationship (Fig. 2) as by welding, riveting or otherwise. A metal plate 13 is preferably arranged in a vertical plane longitudinally of the base between the uprights 6, with its bottom edge preferably seating upon the angle base 5,

and is secured at its opposite ends to the uprights 6 by welding or suitable fastening means. The plate 13 is provided on its inner face with an elongate strap or bridge 14, preferably formed by striking out a rectangular section or web from the body of the plate, to furnish a seating recess for an anchoring tongue 15 carried by the connecting rail or bar 12. The tongue 15 may form part of a bracket 16 affixed, as by rivets 17, to the base of the rail 12; and the vertical web of said rail has a hook 18 adapted to engage over the upper edge of the plate 13. Said bracket preferably has one or more tapering ribs 19 which operate as wedge elements frictionally to lock the anchoring tongue in place behind the bridge 14.

By the simple arrangements above described, the removable rail or tie bar 12 may easily be anchored between the end uprights by dropping the tongue 15 behind the bridge 14 and concomitantly engaging the hook 18 over plate 13. The tight wedging fit between the interengaging parts rigidly supports the end standards in steady, upright position, the length of the bridge member 14 and the interfitting tongue 15 effectually preventing any relative angular movement of the rail and upright in a horizontal plane; yet the interlocking members may readily be separated by striking the underside of the rail 12.

I claim:

1. An article of the class described comprising a pair of end standards each having a rigid, rail-mounting member, a bridge on the inner side of each of said members, and a removable rail connecting said members rigidly to support the standards in upright position, said rail being angular in cross section and having horizontal and vertical web portions, the horizontal portion having a depending tongue at each of its ends adapted to seat behind the respective bridges and against said members, and the vertical portion having integral end hooks engageable over the upper edges of the respective member.

2. An article of the class described comprising a pair of end standards each having

a base, a pair of uprights and a rail-mounting plate resting on the base and secured between the uprights, an elongate section of each plate being struck inwardly to provide
5 a longitudinal bridge, a removable rail connecting said plates rigidly to support the standards in upright position, said rail being angular in cross section and having horizontal and vertical web portions, elongate, de-
10 pending end tongues carried by the horizontal web and wedged behind the respective bridges, and integral hooks at the ends of the vertical web locking over the upper edge of the respective plates.
15 Signed by me at Boston, Massachusetts, this
9th day of May, 1929.

HARRY MINTZ.
